UNITED STATES PATENT OFFICE.

ALBERT RUSH, OF COLUMBUS, OHIO.

FLEXIBLE SHUTTER OR CURTAIN.

No. 926,139.

Specification of Letters Patent.

Patented June 29, 1909.

Application filed June 1, 1908. Serial No. 436,022.

To all whom it may concern:

Be it known that I, ALBERT RUSH, a citizen of the United States, residing at Columbus, in the county of Franklin and State 5 of Ohio, have invented a certain new and useful Improvement in Flexible Shutters or Curtains, of which the following is a specification.

The principal object of this invention is 10 to provide a flexible shutter or curtain composed of jointed slats or sections in which either side can be used as the exposed or weather side, and so that either side, when the shutter or curtain is properly hung, 15 shall shed water effectually.

The invention consists in the construction hereinafter described and particularly pointed out in the claims.

In the accompanying drawings in which 20 one embodiment of the invention is illustrated—Figure 1 is a combined vertical section and isometric perspective of a portion of a curtain or shutter according to the invention; Fig. 2 is a vertical section showing a 25 shutter hung with a smooth side as the weather side; Fig. 3 is a similar section showing the shutter inverted and hung with the joint containing side as the weather side.

30 The slats or sections are preferably made of strips of sheet metal with their longitudinal edges bent as shown to form the jointing members. 4 designates the body of the slat. The opposite edges of the strip 35 are bent to form shoulders 5 and 6 in parallel planes inclined to the general plane of the body of the slat. These shoulders are extended respectively toward the acute angle made by the shoulder with the plane of the 40 slat in the form of rolls, as seen respectively at 5^a and 6^a, the roll 5^a being of larger diameter than the roll 6^a, so that the latter can be slid longitudinally into the former to 45 effect an interlocking connection and prevent their lateral separation when the shutter is flexed as in rolling it up on a roller. It will be noted that the rolls 5^a and 6^a are formed by bending the metal to the side toward which the shoulders are inclined. From

this construction it will be observed that 50 ample flexibility of the shutter is provided for; and also that the thrust of the slats together is borne by the inclined shoulders and especially when the edges of the shutter are confined in guiding channels, as is usual in 55 the class of shutters to which this invention belongs. It will also be observed that by inversion either side is adapted to effectually shed water and can be used as the weather side, as illustrated in Figs. 2 and 3. End- 60 locks, as seen at 7, to prevent longitudinal movement of the slats on each other can be secured by rivets or otherwise to the ends of alternate slats.

What I claim and desire to secure by Letters Patent is:

1. A flexible shutter or curtain constructed chiefly of slats or sections having their opposite edges formed with shoulders parallelly inclined to the general plane of the 70 slats, and with interlocking extensions of said shoulders bent respectively toward the acute and obtuse angles formed by the shoulders with the plane of the slat.

2. A flexible shutter or curtain constructed chiefly of slats or sections having their opposite edges formed with shoulders parallelly inclined to the general plane of the slats, said shoulders being extended and bent respectively toward the acute and obtuse 80 angles formed by the shoulders with the plane of the slats to form interlocking rolls, substantially as described.

3. A slat for the construction of flexible shutters or curtains consisting of a strip of sheet metal having its opposite edges bent to form parallel shoulders inclined to the general plane of the slat, said shoulders being extended and bent respectively toward the acute and obtuse angles formed by the shoulders with the plane of the slat to form rolls adapted to interlock with rolls of similarly 90 formed slats.

ALBERT RUSH.
